BOOK STAND OR SIMILAR ARTICLE

Lloyd E. Magers, 1500 Chicago Ave., Evanston, Ill.

Filed Feb. 24, 1960, Ser. No. 59,502

Term of patent 14 years

(Cl. D33—2)

FIGURE 1 is a perspective view of a book stand showing my new design; and

FIGURE 2 is an end elevational view of the book stand of FIG. 1.

The dominant feature of the design resides in combining within a wheeled open-shelf book stand skeletal inverted U-frames having straight sides but with a pattern of angulation offsetting the angled shelves provided by the forwardly angled top bight portions and side struts, the frame also having a pronounced lateral offset of the rear legs near the base portions of the stand all as shown.

I claim:

The ornamental design for a book stand or similar article, substantially as shown and described.
